Primary Examiner — Vy N Koenig(74) *Attorney, Agent, or Firm* — Dean A. Craine(57) **CLAIM**

The ornamental design for a tripod and holder, as shown and described.

DESCRIPTION

FIG. 1 is a top plan view of a tripod and holder showing my new design, with the tripod in an expanded configuration and an unclaimed electronic device being held in the holder. FIG. 2 is a front elevational view of the invention shown in FIG. 1.

FIG. 3 is a rear elevational view of the invention shown in FIG. 1.

FIG. 4 is a bottom plan view of the invention shown in FIG. 1.

FIG. 5 is a right side elevational view of the invention shown in FIG. 1.

FIG. 6 is a left side elevational view of the invention shown in FIG. 1.

FIG. 7 is a front elevational view of the invention showing the tripod in a collapsed configuration; and,

FIG. 8 is a left side elevational view of the invention shown in FIG. 7.

The broken lines in the drawings depict environmental subject matter, specifically an electronic device, and form no part of the claimed design.

The additional broken lines in FIGS. 2 and 7 depict portions of the tripod and holder that form no part of the claimed design.
